HERMETICALLY SEALED PACKAGE

Edgar Scofield, New York, N. Y., assignor to Anchor Cap & Closure Corporation, Long Island City, N. Y., a corporation of New York

Application February 19, 1929, Serial No. 341,232

10 Claims. (Cl. 215—40)

The present invention relates to the sealing art and more particularly to a hermetically sealed package, and is an improvement upon what is commonly known as side seals, although many of

5 its features are applicable to other constructions.

Certain types of side seal closures are adapted to be stacked one upon another to minimize space and to facilitate shipment. In addition, the stacked caps may be put into feeding devices 10 which will place individual caps on containers as they pass. One of the difficulties encountered with these stacked caps is that the bottoms of the respective caps rest upon the decorated parts of adjacent caps. The relative movement between 15 the two in stacked relation may mar the decoration on the tops of the respective caps during shipment.

Many of the side seal closures have beads in 20 the skirts adapted to seat gaskets, the beads being depressed during the sealing operation to force the gasket against the container. With these caps there is a tendency for the gasket to force its way out of the bead during and subsequent to the sealing operation. Any impairment of the 25 pressure on the gasket by the closure cap will cause a defective seal. Difficulty is also encountered in the opening of these caps due to the fact that the lower edge of the skirt has to be pressed sufficiently close to the side wall of the 30 vessel to hold the gasket in place. As a result, considerable difficulty is encountered in getting a bottle opener to hook under the bottom of the cap. The sharp hooks on the openers frequently tear the edge of the cap, making it useless as a 35 reseal or as a cover cap and preventing its removal by a single operation of the cap opener.

The present invention aims to overcome the difficulties of the present types of caps noted above by providing a cap which is adapted to 40 stack without marring the lacquer on an adjacent cap, which will form a very effective seal on a container, and which may be readily removed in a single operation with a cap opener without impairing its value as a reseal closure. 45 These and other advantages are attained in the present invention.

An object of the invention is to provide an inexpensive closure cap adapted to form a secure seal, the effectiveness of which is not likely to be 50 impaired during shipment or other handling.

Another object of the invention is to provide a secure seal by constricting the skirt of the cap to press the gasket against a container immediately above the reinforced part of the cap, where- 55 by the gasket is held firmly in position.

Another object of the invention is to provide a closure cap adapted to retain a gasket rigidly in position.

Another object of the invention is the provision of a closure cap adapted to stack with other closure caps, the lower edge thereof resting upon the decorated covers without marring the decorations.

Another object of the invention is to provide a closure cap adapted to withstand pressure applied by a hooked cap opener so that the cap can be readily removed without destruction. 10

Another object of the invention is to provide a method of sealing whereby a cap is reinforced immediately below the gasket, and the gasket 15 is pressed against a container immediately above the reinforcement to effect a secure seal.

Other and further objects of the invention will be obvious upon an understanding of the illustrative embodiment about to be described or will 20 be indicated in the appended claims, and various advantages not referred to herein will occur to one skilled in the art upon employment of the invention in practice.

A preferred embodiment of the invention has 25 been chosen for purposes of illustration and description and is shown in the accompanying drawing, wherein

Fig. 1 is a sectional view of a blank in the first stage of manufacture; 30

Fig. 2 is a sectional view of the completed closure cap; and

Fig. 3 is a sectional view illustrating a gasket applied to the closure cap shown in Fig. 2;

Fig. 4 is a sectional view illustrating caps in 35 stacked relation;

Fig. 5 is a fragmentary sectional view illustrating a closure cap applied to a container;

Fig. 6 is a fragmentary sectional view of a different form of cap; 40

Fig. 7 is a fragmentary sectional view illustrating the gasket applied to the cap; and

Fig. 8 is a fragmentary sectional view illustrating the closure applied to a container.

Referring more particularly to the drawing, there is shown a closure cap having a cover portion 1 and a depending skirt 2 with a bead 4 therein. The lower edge of the skirt is rolled inwardly to form an inturned wire edge 5 adapted to serve as the lower side of the bead 4 and as a support for a gasket 6. While the cap can be formed in any suitable manner, preferably the blanks are stamped from sheets of tin into the form shown in Fig. 1. Thereafter the blanks are placed in a rolling machine or operated upon by 50 55 60 65 70 75 80 85 90 95 98

dies to form an inturned wire edge 5 at the bottom thereof. This inturned edge extends sufficiently far inward to hold a gasket in place. The gasket may be applied by machinery or by hand and is generally slightly larger than the skirt of the cap so that it will press resiliently against the side of the bead and can be held in position by the relatively narrow inturned portion at the bottom.

10 In the sealing operation, suitable dies operate upon the bead in a substantially vertical direction to transform it from the shape shown in Fig. 3 to that shown in Fig. 5. The lower part of the bead is pressed inwardly and upwardly as 15 shown by the arrow 7. The inward constriction of the lower part of the bead confines the gasket between the wire edge 5 and the upper side of the bead and the upward constriction of the bead presses the gasket more firmly into engagement 20 with the container. By reason of the reinforced lower edge, it is possible to leave a greater space between the metal of the cap and the side of the container without permitting the gasket to be forced therebetween. The reason for this is that 25 with a strong lower edge, the cap remains in the set position determined by the dies whereas with a single thickness of metal at this point there is likelihood of a stretching action which is not uniform in all cases and, hence, greater care must 30 be taken to prevent the cap being too loose.

In removing the cap an ordinary hooked bottle opener may be applied to the closure similarly to the removal of a cap from a soda pop bottle. The hook engages the wire edge 5, the curved 35 portion of the edge furnishing an excellent hold for the opener, to pull the cap over the side of the container. Due to the several thicknesses of metal in the reinforced edge, there is no likelihood of the hook cutting through the metal or 40 breaking it in any way. Hence, the cap may be removed in a single operation or in a plurality of operations, as desired. Distortion of the bottom of the cap is minimized and this permits a cap to be used as a reseal closure or as a cover 45 cap for the container while the contents are being consumed. An additional feature of the wire edge 5 is that it gives a very smooth surface to the bottom of the cap which permits the caps to be stacked one upon another, as shown in Fig. 50 4, with the rolled lower edge engaging the upper side of the bead of an adjacent cap. It is customary to lacquer the caps or otherwise decorate them to improve their appearance, hence the engagement of a rough edge with the lacquer or 55 other decoration scratches and mars the caps. In many instances, the beauty of the cap sells the product and slight damage to the external portion of the cap is a serious handicap. In the present cap, the rolled edge 5 presents a coated 60 flat surface of metal which rests upon the external portion of the bead. The gaskets 6 engage the conical parts of the caps and prevent any substantial movement so that scratching or other damage to the cap is eliminated.

65 A different form of closure is shown in Figs. 6 to 8 inclusive. It is well known in the sealing art that the rolling inward of metal is difficult due to the fact that the metal must be compressed during the rolling operation. There is a tendency for the metal to wrinkle during the pressing operation, which hinders the rolling and mars the appearance of the cap. On the other hand, this difficulty is not encountered when the free edge of the metal is rolled outwardly because this 70 involves a stretching operation. In Figs. 6 to 8

a blank, for example a blank similar to that shown in Fig. 1, is formed with a wire edge 8 rolled outwardly and set inwardly, as shown in Fig. 6, to a point where it is substantially directly below the depending side of the bead. In other words, the plane of the skirt of the cap passes through substantially the center of the rolled edge. The portion of the wire edge 8 extending inwardly beyond the skirt of the cap forms the lower side of the bead and hence, is 10 a support for the gasket. The sealing operation for applying a cap to the container may be substantially similar to that shown in Fig. 5 or it may be as shown in Fig. 8. In this case, suitable dies are applied to force the entire bead upwardly and inwardly and the lower portion of the bead downwardly. A slightly greater space between the lower edge of the cap 8 and the sidewall of the container may be allowed, if desired, by reason of the seal. This facilitates removal of the cap and 15 is generally advantageous. In general practice, the caps are manufactured as described above, stacked upon each other as shown in Fig. 4, after the gaskets have been assembled with the caps and shipped to canners for application to containers. The caps are placed in suitable feeding machines which place the caps on containers as they pass to a sealing machine. The sealing machine constricts the bead of the cap to form a 20 tight hermetic seal, as shown in Figs. 5 and 9 of 25 the drawing.

It will be seen that the present invention provides a construction which may be readily and inexpensively manufactured. Further, it is adapted to form a more secure seal than those heretofore by reason of the fact that the gasket is held more securely in position and movement thereof is prevented. Shipping of the caps is facilitated due to the fact that they can be stacked without fear of marring the decorated 30 portions thereof. The removal of the caps is facilitated due to the fact that the cap is fully capable of withstanding the concentrated pressure applied by an opening instrument such as a hooked bottle opener. The cap forms a very 35 attractive package and is otherwise fully capable of meeting the requirements of the consuming public.

As various changes may be made in the above embodiment without departing from the spirit 40 of the invention, all matter herein is to be interpreted as illustrative and not in a limiting sense.

Having thus described my invention, I claim:

1. A closure cap comprising a cover portion, a depending skirt adapted to receive a gasket, a 45 gasket in said skirt, and a continuous rolled edge at the bottom of said skirt, said edge being rolled outwardly and set inwardly with respect to the skirt to form a support for the gasket.

2. An article of manufacture comprising an 50 end part and a body part formed of sheet metal and integral with each other, and a continuous rolled edge at the open end of said body part, said edge being rolled outwardly and set inwardly with respect to said body part.

3. As an article of manufacture, a closure cap comprising a cover portion, a depending skirt, and a continuous rolled edge at the bottom of 55 said skirt, said edge being rolled outwardly and set inwardly with respect to the skirt of the cap.

4. A closure cap comprising a cover portion, a depending skirt flared outwardly and downwardly to form the upper and side portions of a bead adapted to receive a gasket, a gasket in 60 said bead, and a continuous rolled edge at the 65

- bottom of said skirt, said edge being rolled outwardly and set inwardly with respect to the skirt to form the lower side of said bead and to form a support for the gasket.
- 5 5. A closure cap comprising a cover portion and a depending skirt having a bead therein adapted to receive a gasket, a gasket in said bead, and a continuous rolled edge at the bottom of said skirt, said edge being rolled outwardly 5 and set inwardly with respect to the skirt to form a support for the gasket in said bead, the outer portion of the bead above the rolled edge being substantially cylindrical.
- 10 6. A sealed package comprising a container, 10 a closure cap having a cover portion and a depending skirt, the lower edge of said skirt being rolled outwardly and set inwardly to form a support for the gasket, and a gasket supported by said rolled edge, said skirt and said inwardly 15 set rolled edge being constricted to force said gasket against the container to form a secure seal thereon.
- 20 7. The method of forming a closure cap with an inwardly extending part for supporting a gasket, which method comprises rolling the lower edge of the cap outwardly into a continuous 20 rolled edge, and setting the rolled edge inwardly to form an inwardly extending projection adapted to support a gasket.
- 25 8. The method of forming a closure cap with an inwardly extending part for supporting a gasket, which method comprises rolling the lower edge of the cap outwardly into a rolled edge, and simultaneously setting the entire rolled edge inwardly so that the outwardly rolled edge extends inwardly of the plane of the skirt of the cap to form an inwardly extending projection adapted to support a gasket. 5
9. The method of forming an article of manufacture comprising a body part closed at one end and open at the other with an inwardly extending part at the open end of the body part, which method comprises rolling the continuous free edge of the body part outwardly into a continuous rolled edge and setting the rolled edge inwardly to form an inwardly extending smooth projection at the open end of the body part. 15
10. A sealed package comprising, in combination, a container and a closure cap having a cover portion and a depending skirt, a bead in said skirt adapted to receive a gasket, the bottom of said skirt being rolled outwardly into a rolled edge, the bottom of said skirt and said rolled edge being set inwardly to support and 20 compress the gasket to form a securely sealed package. 25
